CONSTANT FLOW AERATOR AND SIPHON
BREAKERLeslie E. Lancy, Ellwood City, Pa., assignor to Lancy
Laboratories, Inc., Zelienople, Pa., a corporation of
PennsylvaniaFiled Mar. 12, 1963, Ser. No. 264,614
12 Claims. (Cl. 261—19)

This invention relates to a unit or device for automatically flow-metering, aerating and introducing a conditioning or washing fluid, such as water, into a tank or liquid bath containing a contaminated liquid, such as water, and also to a device that will function as a siphon breaker to prevent back-flow of liquid from the tank into a supply line.

There has been a need for a simple compact unitary device which can be used for the above purpose for conditioning tank liquids or aqueous solutions that have become contaminated, such as in the case of liquids used for laundering, for swimming pools, for chemical and electro-chemical processing, etc. The need is for an inexpensive device that can be connected between a primary fresh liquid or water supply line and a secondary supply line which runs into a liquid tank and is provided with orifices or outlets for introducing the clean or fresh conditioning liquid in such a manner that the contaminants in the tank may be washed out or the liquid therein may be conditioned.

In an ordinary application, a fresh supply of water may be introduced into and along the bottom of the tank in such a manner as to mix thoroughly with the liquid in the tank and loosen solids, so that they may flow to the top level of the tank and be removed from a catch basin along or about an upper portion of the tank and discharged into a waste or sewer pipe. It has been found to be advantageous to aerate the liquid thus being introduced so as to agitate and make it more effective in its conditioning or washing operation. Further, health authorities in many localities require that a siphon-preventing means be provided for preventing any back-flow of liquid from the tank into the primary supply line, if, for example, the pressure supply of the clean liquid is cut off and, in general, to prevent any possible contamination of the liquid source by the liquid of the tank. A siphon-breaking means is useful in this connection even if, as customary, an ordinary shut-off valve is provided in the primary liquid supply line.

In my investigations, I have indicated that the liquid as provided by a primary supply line will vary in pressure in accordance with the pressure at the source and that this is highly disadvantageous from the standpoint that it causes a variation in the flow rate of the washing, treating or conditioning liquid to the tank; it upsets calculated requirements as to the amount of treatment and the time of application of the treatment for a given contaminated solution or liquid. Also, in this connection, it is difficult to accurately set the shut-off valve to give a desired rate of flow. Irrespective of this, the rate will vary, as above indicated, with variations of the pressure of the source.

I have further discovered that there is a need for quickly adapting the installation to a desired flow rate in accordance with the particular type of liquid or aqueous

2

solution being treated, washed or conditioned, and that it is undesirable to provide individual units from the standpoint, for example, of an individual flow rate control unit which is connected through piping to an aerating and siphon breaking unit. This will cause a considerable pressure drop, such that the liquid being introduced may, at times, approach a mere gravity flow to the tank.

In view of the above considerations, it has been an object of my invention to devise an efficient, compact, unitary device which will automatically accomplish in combination the functions of flow control or metering, of aerating, and of siphon breaking, and which will be highly practical from the standpoint of operating ease and effectiveness, of ease of maintenance, and quick and easy adjustment or replacement of its flow control means to provide different selected uniform flow control rates;

Another object of my invention has been to develop a unitary and compact device which will minimize or substantially eliminate any pressure drop as to the source liquid being supplied to the liquid bath or tank;

Another object of my invention has been to devise a compact unitary device whose parts are readily assembled and disassembled with respect to each other and, in such a manner, as to permit easy cleaning and maintenance thereof as well as easy replacement of metering means of a desired flow rate or control characteristics;

A further object of my invention has been to devise and construct a flow rate control device which will also function as an aerating and siphon breaking device.

These and other objects of my invention will appear to those skilled in the art from the following description of an illustrated embodiment thereof as well as from the appended claims.

In the drawings, FIGURE 1 is a somewhat diagrammatic vertical section through a typical installation, showing a device of my invention in a connected or operated relationship therewith;

FIGURE 2 is a greatly reduced top plan view of the installation of FIGURE 1; and

FIGURE 3 is an enlarged sectional view in elevation through an illustrative embodiment of the unitary device of my invention.

In the drawings, I have shown a typical installation in which the device of my invention may be employed. This installation includes a tank 10 containing the liquid to be conditioned, washed or treated, a fresh or clean liquid source or primary supply line 11, a conventional valve 12 in the line 11 for shutting-off and opening flow of liquid therethrough, and a secondary liquid bath or tank supply pipe line 13 which is connected to the primary fresh liquid or primary supply line 11 by a unit 20 of my invention. As shown, the secondary line 13 may extend diagonally across the bottom of the tank 10 and have a series of spaced-apart exit or spray openings 13a therealong for introducing the aerated liquid into the tank and agitating the liquid in the tank. The conditioning or treating action is such that impurities tend to rise to the top of the surface of the liquid in the tank, and to flow over the edge of the side-positioned catch basin 14 from which they may be discharged to the sewer through one or more outlet nipples 15 and a waste discharge pipe 16.

Referring particularly to FIGURE 3 of the drawings, I have shown the compact unitary device 20 of my inven-

tion in its fully assembled operating relationship. The device employs an inlet body part 21, an interfitting and cooperating outlet body part 23, and a coupling or sleeve part 22 for removably-securing the body parts in an aligned and assembled relationship with respect to each other. The inlet part 21 has a larger or enlarged bore 21a which defines an inlet chamber a which corresponds substantially in diameter to the flow diameter of the entering liquid, as supplied by the pipe 11. In this connection, the back end portion of the inlet part 21 has an inner or female threaded bore 21b for receiving a threaded end of the pipe line 11 therein to supply the clean or conditioning liquid under line pressure to the inlet chamber a.

The forward end of the inlet chamber a is connected by a forwardly-inwardly converging, frusto-conically-shaped or nozzle-like bore that defines a chamber b for providing a smooth constriction of the flow of the liquid from the inlet chamber a into the back end portion of a first venturi bore or passageway 21c of reduced substantially uniform diameter. The venturi bore 21c extends longitudinally or axially in alignment with the inlet chamber a, through a forward stem portion 21f. The stem portion 21f is shown of cylindrical shape. The venturi bore 21c defines a main venturi chamber portion c which is shown of the same size or diameter as a secondary venturi chamber portion c' that is defined by a venturi bore or passageway 23k of substantially uniform diameter of the outlet body part 23. The venturi bores or bore portions 21c and 23k, in effect, define an axial or longitudinal venturi chamber for providing a velocity flow of the liquid forwardly into the outlet body part 23.

A recessed portion that projects radially-outwardly with respect to the venturi chambers c and c' is positioned between and is provided by the spaced relation between a forward end or forward edges of the stem portion 21f and a forward ledge or wall portion 23g of a backwardly-open central bore 23f of the outlet body part 23.

The inlet body part 21, substantially intermediate of its length, has an outwardly-projecting annular latching flange 21d which is adapted to cooperate with and be engaged by an inwardly-projecting back end annular flange 22a of the coupling part 22. Forwardly of the flange 21d, the inlet body part 21 has a forwardly-inwardly-declining wedge-shaped or frusto-conical abutment or aligning shoulder 21e which is substantially complementary in slope with a backwardly-outwardly-diverging, wedge-shaped bore or abutment face 23e of the outlet body part 23. It will be noted that the forward end of the abutment face 23e terminates at the back portion of the bore 23f, and that the outer cylindrical periphery of the stem portion 21f of the inlet body part is complementary with or has about the same (slightly smaller) diameter as the bore 23f to provide an aligned, close-fitting, assembled relationship of the inlet body part 21 with respect to the outlet body part 23, in cooperation with the abutment shoulder 21e and the abutment face 23e.

The coupling part 22 has an inner, threaded portion 22b which is adapted to cooperate with an externally-threaded outer peripheral portion 23b of the outlet body part 23 for securely-removably retaining the body parts in an assembled and aligned-flow relationship with respect to each other.

Forwardly of its venturi chamber portion c', an intermediate portion 23d of the outlet body part 23 has a forwardly-diverging vacuum or liquid expansion chamber d which connects with and introduces liquid from the forward end of the venturi bore to an outlet chamber e of enlarged diameter, as defined by an outlet bore 23h. The chamber e is shown as having a flow diameter corresponding to the outflow area into the secondary pipe line 13. The outlet bore 23h terminates in an inner threaded portion 23i which is adapted to secure a forwardly-extending connecting portion 23c of the outlet

body part 23 on the threaded end of the secondary pipe line 13.

A group, and at least a pair of opposed air passageways or ports 23j are, in their inner ends, open or connected to opposite sides of the vacuum chamber d, and slope backwardly-outwardly through the outlet body part 23. The ports 23j are open at their outer ends to a back end portion of an air supply chamber f, adjacent its closed-off back wall. It will be noted that the coupling part 22 has a forwardly-projecting collar or sleeve wall portion 22c which projects substantially from a position transversely-opposite to the recessed portion of the assembly, along the venturi chamber portion c', the vacuum chamber d, and slightly beyond the outlet chamber e and is open at its forward end to the atmosphere. The chamber f acts as a stabilizing influence in preventing any leakage or out-flow of the liquid through the air passageways or ports 23j and, at the same time, supplies air to the liquid under the influence of vacuum in the chamber d, as effected by the liquid flow through the venturi chambers, in order to fully aerate the liquid being introduced into the outlet chamber e and thus, into the secondary pipe line 13. If for any reason the pressure of the liquid being supplied through the primary pipe line 11 should fail, then the passageways 23j act as siphon breakers to prevent any back-flow of liquid from the tank 10, through the secondary supply line 13, to the primary pipe line 11 and thus, back to the source.

A metering element 24 is operatively positioned in the recessed portion between the venturi chambers c and c', it is of a resilient or elastic material that is pressure-sensitive and is shown in the general shape of a washer. The element 24 is provided with an orifice or bore 24a therethrough which is centrally-aligned between the venturi chamber portions c and c' in such a manner as to enhance the venturi action and, at the same time, to always maintain a desired rate of liquid flow. When the pressure of the liquid rises, it acts upon the exposed back face area of the metering element 24 so as to decrease the size of its opening or orifice flow area. On the other hand, when the pressure falls, such orifice area of the element tends to expand and thus increase its size so as to maintain the same flow rate irrespective of pressure. The effective flow control area of the back face of the element 24 may be restricted or controlled by an element or means 25 which may be in the form of a relatively thin, rigid part or element, shown of lesser thickness than the element 24. The element 25 may be in the form of a metal washer provided with a flow bore, orifice or opening 25a therethrough that is larger than the orifice 24a of the element 24; it exposes an annular portion or area of the back face of the resilient element 24 about its orifice 24a to the direct application of the pressure of the fluid. Such annular area lies backwardly from the orifice 24a and in a surrounding relation, immediately adjacent thereto. As shown, the flow control element 24 is securely-positioned with its front or downstream face in face-to-face abutment with the ledge 23g and with its back or upstream face in face-to-face abutment with the washer 25. The element 24 is shown positioned within spacing provided by the joint formed between the stem portion 21f of the inlet part 21 and the central bore of the outlet part 23 and importantly, within the venturi passageway defined by the portions c and c' of such parts. It will be noted that the forward face of the resilient element 24 has a greater area of exposure beyond the ledge 23g than its back face has beyond or radially-inwardly of the washer 25. This has been found to give it a highly accurate and efficient metering action. For providing different selected flow rates, I can substitute an element 24 of different characteristics such as one having a smaller or larger size orifice. By providing an element 25 of a different size of opening, I can control the sensitiveness of the operation of the element 24.

The device 20 has particular application as a unit connected to a washing water supply line that is utilized for rinsing out the liquid in a tank after a chemical or electro-chemical process. By aerating the liquid as it is supplied, I produce an improved action, not only from the standpoint of supplying air to a contaminated liquid bath, but also from the standpoint of thoroughly agitating the contaminated liquid at the bottom of the bath to drive dirt, impurities, etc. upwardly and out over the side weir or catch basin 14. By incorporating metering means, I can supply the conditioning or treating liquid at any desired constant rate, irrespective of ordinary variations in the pressure of the liquid as supplied to the unit.

The parts of the unit 20 are easily demountable and the construction is such that the parts, in effect, automatically align themselves when they are assembled. It is apparent that the device provides for easy maintenance in cleaning-out and, in addition, makes possible the substituting of metering elements of any desired size of flow orifice or of any desired characteristics, so that a selected rate of flow of the liquid can be easily provided. The device makes possible a plurality of functions in one unit and without the pressure drops that would be inherent if a plurality of separate units were connected by piping to each other for this purpose.

The side-positioned air chamber *f*, in combination with the passageways 23*j* assures a hydraulic head on the water within the chamber *d* so as to possibly prevent back-flow. It also prevents any possibility of an out-flow of water through the passageways or ports 23*j*. The overall construction is such as to provide a maximum efficiency of accomplishment of the various functions in combination, and to do so without adversely affecting the pressure of the supply of liquid to the unit and from the unit to the liquid bath.

I claim:

1. A compact unitary device for supplying a conditioning liquid from a source at a substantially constant flow rate and in an aerated condition, to a liquid body to be conditioned which comprises, a pair of interfitting liquid inlet and outlet body parts having cooperating portions for aligning them in a fluid-flow relation with each other, a coupling part removably-securing said body parts in an aligned assembled relationship, said body parts defining a forwardly-extending venturi passageway, said inlet body part having an inlet chamber for supplying liquid from the source into and along said venturi passageway, said outlet body part having a vacuum chamber associated with a forward end of said venturi passageway, said outlet body part having an outlet chamber for receiving liquid from said vacuum chamber, air passageways open at their inner ends to said vacuum chamber and extending backwardly-outwardly through said outlet body part, said coupling part having a skirt wall defining a backwardly-extending forwardly-open air chamber along said outlet body part that is closed at its back end portion with respect to said outlet body part; outer ends of said air passageways being open to the back end portion of said air chamber to prevent venting of the liquid from said vacuum chamber, to supply air to said vacuum chamber for aerating liquid flowing into said outlet chamber, and to prevent a back flow of liquid through the device; and flow control means operatively-positioned within said venturi passageway and between said body parts for supplying the liquid at a substantially constant flow rate to said vacuum chamber.

2. A compact unitary device for supplying a conditioning fluid from a source at a substantially constant flow rate and in an aerated condition to a liquid body to be conditioned which comprises, a pair of interfitting liquid inlet and outlet body parts; said inlet body part having an inlet chamber defined therein and open to its back end portion, having a latching flange projecting outwardly from an intermediate portion thereof and hav-

ing a stem of reduced diameter along its forward end portion; a wedge-shaped abutment shoulder on said inlet body part between said stem and said flange, said outlet body part having a bore projecting inwardly therein 5 from its back end portion and provided with a wedge-shaped entry face and a forward reduced diameter portion to receive said stem, said forward reduced diameter portion having a forward end wall, said wedge-shaped face being constructed to abut said wedge-shaped shoulder and align said inlet and outlet body parts with respect to each other and to position a forward end of said stem in a spaced relation with respect to said forward end wall, said outlet body part having an outlet chamber defined therein and extending backwardly from its forward end portion and open to the spacing between the forward end of said stem and said forward end wall, said inlet and outlet body parts defining a venturi passageway between said inlet and said outlet chambers, flow control means constructed to provide a substantially 15 constant flow rate of the fluid, said flow control means being operatively-positioned within the spacing between the forward end of said stem and said back end wall of said outlet body part and having a flow orifice within and in cooperative alignment with said venturi passageway, a coupling part having a back end flange to engage said latching flange, and means for removably-securing said coupling part on said outlet body part.

3. A compact unitary device as defined in claim 2 wherein said venturi passageway comprises, a back portion and a forward portion connected by the spacing between the forward end of said stem and said back end wall, and the forward portion is of relatively shorter length than the back portion thereof.

4. A compact unitary device as defined in claim 2 wherein said flow control means comprises, a resilient element having a flow orifice therein, a backwardly-positioned rigid element in face-to-face abutment with a back face of said resilient element and having a flow orifice therethrough of larger diameter than the flow orifice through said resilient element, and a forward ledge in face-to-face abutment with a front face of said resilient element and having a flow orifice therethrough of a larger diameter than the flow orifice of said rigid element.

5. A compact unitary device for aerating and supplying a conditioning liquid from a source at a substantially constant flow rate and in an aerated condition to a liquid body to be conditioned which comprises, a pair of interfitting liquid inlet and outlet body parts having cooperating portions for aligning them in a liquid-flow relation with each other, means removably-securing said body parts in an aligned assembled relation, said body parts defining a forwardly-extending venturi bore and a recessed portion within said venturi bore, said inlet body part having an inlet chamber for supplying liquid from the source into and along said venturi bore, an outlet chamber in said outlet body part for supplying liquid to the liquid body to be conditioned, flow control means operatively-positioned in said recessed portion for supplying the liquid at a substantially constant flow rate 45 to said outlet chamber irrespective of the pressure of the liquid introduced into said inlet chamber, a vacuum chamber associated with a forward end of said venturi bore, and air passageways inclining forwardly-inwardly through and open at their back ends outwardly from said outlet body part and open at their front ends inwardly to said vacuum chamber for aerating the liquid flowing into said outlet chamber and preventing a back-flow of the liquid from the liquid bath through the device.

6. A device as defined in claim 5 wherein said means removably-securing said body parts is a coupling part, said coupling part has a skirt wall defining a backwardly-extending forwardly-open air chamber along said outlet body part, and said air passageways slope backwardly into and are open at their outer ends to a back end por-

tion of said air chamber to prevent venting of the liquid from said vacuum chamber.

7. A device as defined in claim 5 wherein, said recessed portion divides said venturi bore adjacent its forward end, and said flow control means is operatively-positioned in said recessed portion to define a through-orifice between divided portions of said venturi bore.

8. A device as defined in claim 5 wherein, said flow control means has a resilient washer-like element provided with a flow orifice therethrough in alignment with said venturi bore, said resilient element has means to automatically control the size of its orifice in accordance with the pressure of the liquid being introduced into said inlet chamber, and said flow control means has a relatively rigid element provided with a flow orifice therethrough larger than and in alignment with the orifice of said resilient element, and said relatively rigid element is positioned in face-to-face abutment with a back face of said resilient element for limiting the area of application of pressure force of the liquid on said resilient element.

9. A compact unitary device for aerating and supplying a liquid such as washing water forwardly at a predetermined substantially constant rate of flow from a primary fresh liquid supply line to a secondary tank liquid supply line for conditioning the liquid in a tank which comprises, a pair of interfitting body parts, a coupling body part removably-securing said body parts in a forwardly-aligned assembled relation with each other, one of said body parts being an inlet part for connection at its back end portion to the primary supply line for receiving liquid under pressure therefrom, the other of said body parts being an outlet part for connection at its forward end to the secondary supply line for supplying aerated liquid to the liquid in the tank; said inlet part having a bore open to and extending from its back end to receive liquid from the primary supply line and define an inlet chamber, and having a first venturi bore of reduced diameter extending from a forward end of said inlet chamber and open to a forward end of said inlet part; said outlet part having a second venturi bore of substantially the same diameter as and open to and extending from its back end in substantial longitudinal alignment with the forward end of said first venturi bore, and having a connecting bore of larger diameter than and connected to a forward end of said second venturi bore and open at its forward end to define an outlet chamber; the forward end of said inlet part defining a recessed portion with respect to said outlet part between the forward end of said first venturi bore and the back end of said second venturi bore, a resilient flow control element operatively-positioned in said recessed portion and having a through orifice of reduced diameter with respect to and connecting said venturi bores; opposed face abutment means cooperating with and seating said resilient element between said inlet and outlet parts within said recessed portion, whereby said element will flex about its said orifice in accordance with the pressure of liquid passing forwardly from said first venturi bore into said second venturi bore to provide a substantially constant rate of flow of the liquid based on the normal flow diameter of the orifice; said connecting bore defining a vacuum chamber; and a group of radially-inwardly-forwardly-converging opposed passageways in said outlet part connecting said vacuum chamber to the atmosphere, whereby air will be drawn into the liquid moving forwardly from said vacuum chamber into said outlet chamber during a normal forward pressure flow of liquid through the device, and whereby the vacuum chamber will be vented to the atmosphere to prevent a back flow of liquid through the device.

10. A device as defined in claim 9 wherein, said recessed portion is defined between forward edges of a forwardly-projecting stem-like forward end portion of said inlet part and an opposed ledge portion of said outlet part, said seating means has a relatively rigid washer-like

element positioned in face-to-face abutment between a back face of said resilient element and said forward edges of said stem-like forward end portion, said washer-like element has an orifice therethrough of larger diameter than and positioned in alignment with the orifice of said resilient element, and said washer-like element has an area about its orifice that projects radially-inwardly beyond the diameter of said first venturi bore for limiting the flow control area of said resilient element about its orifice.

11. A device as defined in claim 9 wherein said coupling part has a forwardly-projecting annular wall portion positioned in a radially spaced-apart relation with respect to the outer periphery of a forward portion of said outlet part and defines an air chamber therewith which at its forward end is open to the atmosphere and at its back end is open to outer ends of said group of opposed passageways.

12. A compact unitary device for aerating and supplying a liquid such as washing water forwardly at a predetermined substantially constant rate of flow from a primary fresh liquid supply line to a secondary tank liquid supply line for conditioning liquid in a tank which comprises, an inlet body part having a threaded back connecting portion for securing it to the primary supply line and having a bore defining an inlet chamber of substantially the flow diameter of said threaded back connecting portion; said inlet body part having a forwardly-projecting stem-like forward end portion, and having a venturi bore connected at its back end to the forward end of said inlet chamber and open to the forward end of said stem portion; said inlet body part having a radially-outwardly-projecting latching flange forwardly of said threaded back connecting portion, and having a forwardly-declining-wedge-shaped outer shoulder between said latching flange and said stem portion; an outlet body part having a threaded forward connecting portion for securing it to the secondary supply line, having a bore defining an outlet chamber of substantially the flow diameter of said threaded forward connecting portion, and having an outwardly-backwardly-diverging wedge-shaped abutment face open to its back end for aligning with and receiving said outer shoulder of said inlet body part; said outlet body part having a backwardly-open central bore therein from said abutment face to receive said stem portion therein, said outer shoulder and said abutment face positioning said inlet body part with the forward end of its stem portion in a spaced recess-defining relation with a front end of said central bore of said outlet body part, said outlet body part having a venturi bore in forward alignment with the venturi bore of said inlet body part, said outlet body part having a forwardly-diverging bore between a forward end of its venturi bore and a back end of said outlet chamber that defines a vacuum chamber therebetween, said outlet body part having a threaded portion about its outer periphery, a sleeve-like coupling part having an inner threaded portion adapted to engage the threaded portion of said outlet body part and having an inwardly-projecting flange at its back end for latch-engaging with said latching flange of said inlet body part to hold said inlet body part in a backwardly-aligned position with said outlet body part when the inner threaded portion of said coupling part is in cooperating engagement with the threaded portion of said outlet body part, said coupling part having a forwardly-projecting cylindrical wall portion positioned in a spaced-apart relation with respect to and along said outlet body part and defining an air chamber therewith that is forwardly-open to the atmosphere at a position slightly beyond said outlet chamber, and at least a pair of passageways projecting downwardly-inwardly in an opposed relation through said outlet body part from a back end portion of said air chamber into said vacuum chamber for supplying air to forwardly moving liquid in the device from said air chamber and for preventing a

back-flow of liquid within the device, flow-control means operatively-seated in the recess defined between the forward end of said stem portion and the front end of said central bore and having a flow orifice therethrough in alignment with the forward end of the venturi bore in said inlet body part and the back end of the venturi bore in said outlet body part; and said flow control means being sensitive to pressure of liquid flowing into the device to maintain a substantially constant rate of liquid flow out of the device, irrespective of the pressure of the liquid introduced into said inlet chamber and dependent upon the normal diameter of said flow orifice.
